UNITED STATES PATENT OFFICE.

ELLIS I. O'NEILL AND WILLIAM N. TAGGART, OF PHILADELPHIA,
PENNSYLVANIA.

THREAD-FEEDING DEVICE FOR CIRCULAR-KNITTING MACHINES.

No. 818,908.

Specification of Letters Patent.

Patented April 24, 1906.

Application filed April 29, 1904. Serial No. 205,502.

To all whom it may concern:

Be it known that we, ELLIS I. O'NEILL and WILLIAM N. TAGGART, of Philadelphia, in the State of Pennsylvania, have invented certain new and useful Improvements in Thread-Feeding Devices for Circular-Knitting Machines, of which the following is a specification, reference being had to the accompanying drawings.

10 Our invention relates to guiding and splicing mechanism by which the main thread may be continuously fed to the fabric and a supplemental or splicing thread may be intermittently fed, together with the main thread, 15 and at certain times separated therefrom cleanly severed and withheld from said fabric.

As hereinafter described, our invention comprises a thread-guiding frame provided 20 with a channeled block through which both threads pass, said block being arranged to reciprocate to raise the splicing-thread into contact with the main thread when required, so as to be carried along therewith by frictional engagement; a pair of shear-blades arranged to open for the passage of said threads when the splicing-thread is being fed and arranged to close and shear said splicing-thread when it is to be withheld, and an oscillatory 25 plate arranged to separate said threads slightly in advance of the shearing operation to hold the main thread up out of the path of the shear-blades when the splicing-thread is being sheared.

30 In the accompanying drawings, Figure I is a side elevation of a thread-guide and splicing device embodying our invention. Fig. II is a vertical sectional view taken on the line II II in Figs. I and III. Fig. III is a vertical sectional view of a portion of the splicing mechanism. Fig. IV is a vertical sectional view taken on the line IV IV in Fig. I. Fig. V is a perspective view of the oscillatory separating-plate.

40 In said figures, 1 is a standard suitably mounted in the bed-plate 2 of a circular-knitting machine adjacent to the knitting-cylinders. The thread-guiding frame 3, supported by said standard 1, extends radially to a position substantially central with respect to the knitting-cylinders and is provided at its end with the eye 4, through which the main thread 5 and splicing-thread 6 are fed to the thread-guide on the knitting-machine, which may

be of any ordinary construction and is not 55 shown. Said frame 3 comprises horizontally-extending arms 7 7, (best shown in Fig. II,) which are provided with eyes 8 8, either of which may be used for the main thread 5, and intermediate of said eyes 8 8 is the eye 9 for 60 the splicing-thread 6. The lug 10 on the frame 3 in front of said eye 9 is provided with thread-eyes 11 and 12, respectively, for the main thread 5 and the splicing-thread 6, centrally disposed one above the other, as 65 best shown in Fig. III. Adjacent to the thread-eye 4 said frame 3 is provided with an upwardly-extending lug 14, to which is pivotally supported a thread-guiding tube 15, through which the thread passes to the take-up lever 17. Said lever 17 is pivoted intermediate of its length to the lug 18 on the frame 3 and is counterbalanced by the spiral spring 19, which extends from the upper end of said lever 17 to the collar 20, fixed on the 70 standard 1.

The thread-guiding block 22, interposed between the lug 10 and the lug 14, is provided with the longitudinal channel 23 (best shown in Figs. II and III) and is supported for vertical reciprocation by the plunger 25, which extends through the frame 3 and is pivoted at its lower end to the lever 26, which latter is fulcrumed intermediate of its length to the lug 27, depending from the frame 3. The 80 other end of said lever 26 is provided with the slot 30, engaging the pin 32 on the collar 34, adjustably secured to the upper end of the reciprocating sleeve 35 by the set-screw 36. Said sleeve 35 is mounted for vertical 85 reciprocation in aligned brackets 37 and 38, secured to the standard 1, as shown in Figs. II and IV.

The lower end of the sleeve 35 carries the projecting arm 41, provided at its free end 90 with the pin 42, engaging the slot 43 in the outer end of the lever 45, said lever being fixed at its opposite end on the rock-shaft 50. Said rock-shaft 50 is journaled in the bracket 49 on the machine bed-plate 2 and may be 100 oscillated manually by the lever 51 or automatically by any part of the knitting-machine capable of imparting suitable movement.

The thread-guiding channel-block 22 has 105 the thread-eye 24 extending obliquely through its bottom wall from the channel 23, and directly beneath said eye 24 the frame 3

is provided with a pad 21, of leather or other material, adapted to frictionally engage the splicing-thread 6 under the pressure of the block 22 when the latter is lowered, as herein-after described.

In order that the end of the splicing-thread 6 may be carried into the fabric at each splicing operation by mere frictional engagement with the main thread 5, it is desirable that it may be initially free from the usual resistance of unwinding from its bobbin. Therefore we provide a take-up lever 54, fulcrumed at 55 on the lug 27, as shown in Fig. III, and having its slot 56 engaging the pin 57, extending from the plunger 25, so that the downward movement of said plunger at the end of each splicing operation clamps the thread 6 upon the pad 21 and simultaneously uplifts the opposite end of said lever 54, which draws the thread 6 in its eye 58 above a straight line between the thread-eye 9 and the thread-guide bar 60, under which latter the thread comes from its bobbin, and thereby takes up enough of said splicing-thread 6 from its bobbin to freely engage the main-thread 5 when the lever 54 returns to its lower position.

As best shown in Fig. II, the two shear-blades 64 are mounted on the pivot 65 at the forward end of the block 22, so as to embrace the thread 6, extending through the channel 23 in said block, and are provided with the arms 66, projecting below the overhanging ends 67 of the plates 70, which latter are stationary on opposite sides of the frame 3, so as to open said shears when the block 22 rises. Said shears are closed when the block 22 descends by engagement of their arms 66 with the ridges 71 on the frame 3, which latter is recessed at 72, as shown in Figs. II and III, to receive the end of the block 22, carrying said shears.

As it is desired to sever only the splicing-thread 6 at predetermined intervals, it is necessary to then separate it from the main thread 5, and for this purpose we provide the arm 73, which is conveniently mounted to oscillate on the stud 74, carried by the block 22, and has the notched plate 76 at its free end, extending transversely between the threads 5 and 6. Said arm 73 oscillates from the position shown in Fig. I, where the thread-notch 77 in said plate 76 is lowermost, and the threads 5 and 6 are separated to the position shown in Fig. III, where the plate 76 is in the rear of the block 22. In the last-named position, the notch 77 being uppermost and the block 22 raised, the main thread 5 passes through said notch and along the bottom of the channel 23 in engagement with the splicing-thread 6 and both pass forward as one thread between the open shears 64 into the fabric. Said thread-separating plate 76 is alternately oscillated from end to end of the block 22 by gearing comprising the pinion 80,

secured to the arm 73 and the sector 81, engaged therewith and mounted for oscillation on the pivot 82 in the block 22. Said sector 81 is provided with the crank-stud 83, engaging the slot 84 in the forward end of the arm 85, which latter is supported and raised and lowered by the rod 86. Said rod 86 is mounted to reciprocate in the sleeve 35, before described, and is provided near its lower end with the pin 87, extending through the slot 88 in said sleeve, as shown in Fig. IV. Said sleeve 35 incloses the coiled spring 89, which tends to uplift the rod 86, but is normally restrained by the detent-hook 90, pivoted to the bed-plate 2 and normally engaged with said pin 87 under pressure of the spring 91. (Shown in Fig. I.)

The operation of our device is as follows: The parts are normally in the relation illustrated in Fig. I, wherein the main thread 5 is being continually fed from its bobbin under the thread-guiding arm 60, through the eyes 8 and 11 to the channel-block 22, over the separating-plate 76, through the tube 15 and eye 4 to the ordinary thread-guide on the knitting-cylinder, and the splicing-thread 6 extends from its bobbin under the thread-guiding arm 60, through the thread-eyes 58, 9, 12, and 24 and the channel 23, and is clamped between the bottom of the block 22 and the pad 21. When it is desired to reinforce the fabric—as, for instance, in knitting the heel and toe pockets of a stocking—the shaft 50 is rocked, and by the lever 45 and arm 41 the sleeve 35 is depressed and by rocking the lever 26 uplifts the plunger 25 and channel-block 22 until the splicing-thread 6, lying therein, is brought into contact with the moving main thread 5 and is carried along therewith to the fabric by frictional engagement. The upward movement of the channel-block 22 occasions the opening of the shear-blades 64 by the contact of their arms 66 with the plates 70, oscillates the separating-plate 76 from the front to the rear of said block 22 by the engagement of the pinion 80 with the sector 81, and swings the end of the take-up lever 54 down, so as to bring its thread-eye 58 in alinement with the guide-bar 60 and eye 9 to slacken the splicing-thread 6, so that it may be freely carried along with the main thread 5. When it is desired to terminate feeding the splicing-thread 6, the detent-hook 90 is pressed back to release the pin 87 and permit the spring 89 to uplift the rod 86 within the sleeve 35. The upward movement of said rod 86 with its arm 85 oscillates the sector 81, and the pinion 80 meshes therewith, which oscillates the separating-plate 76 from the rear to the front of the channel-block 22 while said block is still raised, and thereby separates the threads 5 and 6. Said plate 76 being then in the position shown in Fig. V, the main thread 5 passes over the straight upper edge thereof, while the

splicing-thread 6 passes through the inverted notch 77. Thereupon the shaft 50 being again rocked to uplift the sleeve 35, the lever 26 is thereby rocked to lower the block 22 with its plunger 25 to close the shear-blades 64, and thus cleanly sever the splicing-thread 6, passing therethrough. Contemporaneously said splicing-thread 6 is clamped between the block 22 and the pad 21, and the take-up lever 54 is raised to the position shown in Fig. I, so that the device is again arranged for knitting the main thread 5 alone.

We do not desire to limit ourselves to the precise details of construction and arrangement herein shown, as it is obvious that various modifications may be made therein without departing from the essential features of our invention.

We claim—

1. In a thread-feeding device, the combination with a frame; of a thread-carrying channel-block, mounted to move on said frame; a pair of shear-blades carried by said block; and, means arranged to open and close said blades in definite relation with the movement of said block, substantially as set forth.

2. In a thread-feeding device, the combination with a frame; of a thread-carrying channel-block mounted to reciprocate on said frame; a pair of shear-blades mounted on said block and arranged to open and close in accordance with the movement of said block; a thread-separating member mounted on said block; and, means arranged to actuate said member, substantially as set forth.

3. In a thread-feeding device, the combination with a frame; of a thread-carrying block mounted to reciprocate on said frame; a pair of shear-blades mounted on said block and arranged to open and close in accordance with the movement of said block; a thread-separating member mounted to oscillate on said block; and, means arranged to oscillate said member from end to end of said block, substantially as set forth.

4. In a thread-feeding device, the combination with a frame; of a thread-carrying channel-block mounted to reciprocate on said frame; a pair of shear-blades mounted on said block and arranged to open and close in accordance with the movement of said block; a thread-separating member mounted to oscillate on said block; a pinion secured to said member at its axis; a sector pivoted to said block, in mesh with said pinion; and, means arranged to oscillate said sector, substantially as set forth.

5. In a thread-feeding device, the combination with a frame; of a thread-carrying channel-block mounted to reciprocate on said frame; a pair of shear-blades mounted on said block and arranged to open and close in accordance with the movement of said block; a thread-separating member mounted

to oscillate on said block; a pinion secured to said member at its axis; a sector pivoted to said block, in mesh with said pinion; a reciprocatory rod arranged to oscillate said sector; a pin on said rod; and, a detent arranged to engage said pin, substantially as set forth.

6. In a thread-feeding device, the combination with a frame; of a thread-carrying channel-block mounted to reciprocate on said frame; a pair of shear-blades mounted on said block and arranged to open and close in accordance with the movement of said block; a thread-separating member mounted to oscillate on said block; a pinion secured to said member at its axis; a sector pivoted to said block, in mesh with said pinion; a reciprocatory rod arranged to oscillate said sector; a detent arranged to normally engage said rod; and, a spring arranged to shift said rod and thereby oscillate said separating member when said detent is released, substantially as set forth.

7. In a thread-changing device, the combination with a frame; of a thread-carrying block mounted to reciprocate on said frame; a pair of shear-blades mounted on said block and arranged to open and close in accordance with the movement of said block; a thread-separating member; means to operate said member; and, a thread-take-up device arranged to operate in definite relation with the movement of said block, substantially as set forth.

8. In a thread-feeding device, arranged to continuously feed a main thread and to intermittently feed a splicing-thread along with said main thread; the combination with a frame; of a reciprocating thread-carrying channel-block mounted in said frame, arranged to effect the clamping of said splicing-thread between said block and said frame; a thread-separating member arranged to separate said main thread from said splicing-thread; a pair of shear-blades arranged to shear said splicing-thread; and, a thread-take-up lever arranged to move in accordance with the movement of said channel-block, substantially as set forth.

9. In a thread-feeding device, arranged to continuously feed a main thread and to intermittently feed a splicing-thread along with said main thread; the combination with a frame; of a channel-block arranged to move in said frame; a thread-separating member arranged to separate said main thread from said splicing-thread; means arranged to actuate said separating member independently of the movement of said block; means arranged to shear said splicing-thread; and, means arranged to intermittently take up said splicing-thread between said channel-block and the source of said thread, substantially as set forth.

10. In a thread-feeding device, arranged to continuously feed a main thread and to inter-

- 4
- mittently feed a splicing-thread along with said main thread; the combination with a frame; of a reciprocatory thread-guiding block mounted in said frame; a thread-separating member arranged to oscillate and separate said main thread from said splicing-thread; means arranged to actuate said separating member independently of the movement of said block; a pair of shear-blades arranged to sever said splicing-thread; and, means arranged to reciprocate said block and thereby clamp said splicing-thread and simultaneously take up said splicing-thread, between its clamped portion and its source, substantially as set forth.
11. In a thread-feeding device, arranged to continuously feed a main thread and to intermittently feed a splicing-thread along with said main thread; the combination with a frame; of a reciprocatory channel-block; a pair of shear-blades arranged to sever said splicing-thread in accordance with the movement of said channel-block; a thread-separating member arranged to oscillate; means arranged to oscillate said member independently of the movement of said channel-block; and, a thread-take-up lever arranged to oscillate in accordance with the movement of said channel-block, substantially as set forth.

12. In a thread-feeding device, the combination with a frame; of a thread-carrying channel-block mounted to reciprocate on said frame; a lever attached to said frame; a sleeve attached to said lever; a rock-shaft having a lever-arm arranged to reciprocate said sleeve; a pair of shear-blades pivoted to said block and arranged to open and close in accordance with the movement of said block; a thread-take-up lever pivoted to said frame; a thread-separating plate pivoted on and arranged to oscillate from end to end of said block; a pinion secured to said separating-plate at its axis; a sector pivoted to said block, in mesh with said pinion; a rod mounted to slide within said sleeve and arranged to oscillate said sector; a spring tending to shift said rod; a pin extending from said rod; and, a detent arranged to engage said pin against the pressure of said spring, substantially as set forth.

In testimony whereof we have hereunto signed our names, at Philadelphia, Pennsylvania, this 26th day of April, 1904.

ELLIS I. O'NEILL.
